UNITED STATES PATENT OFFICE.

PHILIP DOUGLAS LEE, OF LONDON, ENGLAND.

CARBURETER FOR INTERNAL-COMBUSTION ENGINES.

998,355.

Specification of Letters Patent. Patented July 18, 1911.

Application filed September 24, 1910. Serial No. 583,554.

To all whom it may concern:

Be it known that I, PHILIP DOUGLAS LEE, a subject of His Majesty the King of Great Britain, residing at 300 St. James Court, 5 Buckingham Gate, London, England, gentleman, have invented certain new and useful Improvements in or Relating to Carbureters for Internal-Combustion Engines; and I do hereby declare the following to be 10 a full, clear, and exact description of the invention, such as will enable others skilled in the art to which it appertains to make and use the same.

This invention relates to carbureters for 15 internal combustion engines whereof the auxiliary air valve is opened by suction against spring resistance, and has for its object to insure that at all openings of the throttle, irrespective of engine speed, the 20 additional air required shall be supplied through the valve aforesaid in the correct and proper proportion, that is to say that at all engine speeds and all throttle openings the proportions of air and petrol constituting the mixture taken by the engine 25 shall remain constant and substantially invariable.

Figure 1, is a sectional elevational view of a carbureter embodying my invention; 30 Fig. 2 is a plan view, parts being shown in section, of the means for adjusting the tension of the tensioning element of the auxiliary air valve; and Fig. 3 is a sectional plan view of a modified form of the invention.

It is obvious that in order to attain this result the spring resistance to the opening of the auxiliary air valve must be regulated in accordance with the opening of the 40 throttle in such a manner that said spring resistance will be increased in direct proportion to the opening of the throttle, and vice versa since the spring resistance which permits the said valve to open to the extent required to pass the correct proportion of air 45 when the throttle is fully open would clearly be too great were the throttle partially closed and the suction in consequence reduced. Means have therefore to be pro-

vided for regulating the said spring resistance to suit the circumstances and hitherto independent hand regulation has sometimes been used, the judgment of the operator having to be relied on for making the adjustment, and the system having the further 55 disadvantage that an additional handle or control requires attention.

According to the present invention I provide means whereby the spring resistance to the opening of the said auxiliary air valve 60 is automatically regulated by the act of opening and closing the throttle valve, in such a manner that the opening of the latter automatically increases said spring resistance, and vice versa. Thus the same 65 movement of the pedal or other control which operates the throttle also effects the automatic regulation of the said spring resistance in the manner above set forth.

It will be obvious that my invention as 70 above outlined is susceptible of very considerable modifications in the manner of performing it, and I will now describe by way of example and with reference to the annexed drawings, two suitable embodiments of the invention.

Similar letters refer to corresponding parts in all the figures.

Referring to Fig. 1 which shows in sectional elevation an application of my invention to a carbureter of well known type, and to the part plan view Fig. 2, *a* indicates the throttle valve, *b* the inlet pipe for the mixture, *c c* pipes leading right and left from the throttle to the engine, and *d* an auxiliary 80 air valve of known construction provided with the usual dashpot *d'*, said valve being held closed by a light spring *e* located and held in compression between a washer *f* on the valve spindle *d* and nut *g* rotatable on 85 a quick pitch screw thread formed on a sleeve or elongated bearing *h* extending upward from the cover *h* of the air valve. By partially rotating the nut *g* by its arm *g'* Fig. 2, (hitherto usually effected by independent hand adjustment) the resistance 90 of the spring *e* to the opening of the air valve *a* may be regulated.

Now according to my invention I cause the movement of the throttle valve *a* to automatically effect the regulation in the manner above set forth of the spring resistance to the opening of the air valve *d* as follows:—The throttle operating rod *a'*, which is worked from the usual pedal or control, engages the forked end of the lever *i* conveniently fulcrumed at *k*, and with the other arm of this lever is connected one end of a rod *l* whose other extremity is connected with the arm *g'* extending from the nut *g* aforesaid. It will thus be seen that the same movement of the pedal or other control which actuates the throttle valve will also effect the automatic regulation of the resistance of the spring *e* to the opening by suction of the auxiliary air valve *d*, in such a manner that opening of the throttle will increase the spring resistance and vice versa. Adjustment of the effective length of the connecting rod *l* may be obtained by the adjusting nuts *l'* on said rod; and by providing a series of holes *m* in the arm of lever *i* for the reception of the end of the connecting rod *l*, the speed of motion of the latter relatively to that of the throttle operating rod *a'* may also be regulated. *n* indicates a suitable joint which may conveniently be placed in the connecting rod *l*. An adjustable stop may be provided to arrest further movement of the nut *g* when the minimum desirable spring resistance is reached.

35 In the embodiment of the invention shown in Fig. 3, which illustrates in sectional elevation an application thereof to another form of carbureter, the automatic regulation in the manner above set forth of the spring resistance to the opening by suction of the air valve *d* is effected as follows:—The axes of the throttle valve *a* and the auxiliary air valve *d* are here arranged in line and between the valves is interposed the spring *e'*. When the throttle is moved upward to open it, the spring *e'* engages the valve *d*, its compression increasing in direct proportion to the opening of the throttle, whereby the spring resistance to the opening of the air valve *d* is automatically increased. As shown the spring *e'* is slightly separated from the air valve *d* when the throttle is closed, and at the commencement of the opening movement the spring resistance to the opening of the air valve is provided by the spring *e* only, which has a very light pull, say about $1\frac{1}{2}$ ounce; continuation of the opening movement brings the spring *e'* into action and adds its resistance to that of spring *e*. The spring *e* may, however, be entirely dispensed with if preferred, and reliance for spring resistance to the opening of the valve *d*

placed solely on the spring *e'*, which in this case would be lengthened so as to be in 65 slight compression between the throttle valve *a* and the air valve *d* when the throttle is fully closed.

In conclusion I would observe that I do not confine or limit myself to the particular 70 constructions described and illustrated in the drawings since the same may obviously be considerably varied without in any way departing from my invention.

What I claim and desire to secure by Letters Patent of the United States is:—

1. In a carbureter for internal combustion engines, the combination with a throttle valve and means for operating the same, of a spring influenced auxiliary air valve 80 adapted to be opened by engine suction; and means whereby said throttle valve may be opened and the resistance to opening of said air valve proportionately increased, or said throttle valve may be closed and the 85 resistance to opening of said air valve proportionately decreased, whereby the proportions of the combustible mixture for engine operation are kept constant at all engine speeds and throttle openings. 90

2. In a carbureter for internal combustion engines, the combination with a throttle valve and means for operating the same, of an auxiliary air valve adapted to be opened by engine suction, a spring tending 95 to normally hold said auxiliary valve to its seat and means whereby said throttle valve may be opened and the resistance to opening of said air valve proportionately increased, or said throttle valve may be closed 100 and the resistance to opening of said air valve proportionately decreased, whereby the proportions of the combustible mixture for engine operation are kept constant at all engine speeds and throttle openings. 105

3. In a carbureter for internal combustion engines, the combination with a throttle valve having an elongated operating rod, of an auxiliary air valve adapted to be opened by engine suction, a spring encircling the stem of said auxiliary valve, a threaded sleeve embracing said stem, a nut movable on said sleeve and adapted by its movement to vary the tension of said spring, an operating rod for said nut, and a lever 115 engaging both said rods and adapted when moved to concurrently move said throttle valve and said nut.

4. In a carbureter for internal combustion engines, the combination with a throttle valve having an elongated operating rod, of an auxiliary air valve adapted to be opened by engine suction, a spring encircling the stem of said auxiliary valve, a threaded sleeve embracing said stem, a nut movable 120 on said sleeve and adapted by its movement 125

to vary the tension of said spring, a jointed operating rod for said nut, and a lever having a fork at one end for engaging the operating rod of the throttle valve and having a series of holes in its other end for reception of one end of the jointed operating rod of the said nut.

In testimony whereof I have hereunto set my hand in the presence of two witnesses.

PHILIP DOUGLAS LEE.
